UNITED STATES PATENT OFFICE.

VAN EVERY EDWARDS, OF DECATUR, ILLINOIS, ASSIGNOR OF ONE-HALF TO OLIVE B. WHEELAND, OF RIVERTON, ILLINOIS.

ROTARY STEAM-ENGINE.

1,211,831.

Specification of Letters Patent.

Patented Jan. 9, 1917.

Application filed March 13, 1916. Serial No. 83,877.

To all whom it may concern:

Be it known that I, VAN EVERY EDWARDS, a citizen of the United States, a resident of Decatur, in the county of Macon and State 5 of Illinois, have invented new and useful Improvements in Rotary Steam-Engines, of which the following is a specification.

My invention relates to improvements in rotary steam engines and the principal object is to provide a mechanism of that character which will develop high power and efficiency with a minimum consumption of steam.

To the accomplishment of the foregoing 15 and such other objects as may hereinafter appear, my invention consists in the combination, construction and arrangement of parts hereinafter described and then sought to be defined in the appended claims, reference being had to the accompanying drawings forming a part hereof, and which show merely for the purpose of illustrative disclosure, a preferred embodiment of my invention, it being understood that various 25 changes may be made in practice within the scope of the claims without digressing from my inventive idea.

In the drawings: Figure 1 represents an elevation of a plurality of engines constructed according to my invention, one of the motors being shown in section; Fig. 2 is a side elevation of one of the motors, the cover plate being removed, and parts being shown in section to facilitate disclosure.

Referring now to the drawings, the numeral 1 designates suitable supporting members which may be secured to a concrete foundation or in any other suitable manner. On these supporting members are mounted 40 the casings of the engine and also the supports for the shaft. This shaft is designated by the reference character 2 having the bearings 3 on supports 4 and is preferably provided at an intermediate point with 45 the clutch mechanism 5, whereby the two parts of the shaft may be coupled or disconnected as desired.

6 and 7 designate suitable fly wheels, 8 a governor driven by means of the belt and 50 pulley arrangement 9.

10 indicates a steam header having the supply pipes 11 leading into the separate engines.

Each engine or motor includes the casing 55 12 which is bolted to the supports and which

has the cylindrical compartment 13 therein. In this compartment revolves the rotor 14 which is keyed or otherwise secured to the shaft 2, the shaft 2 running loosely within the casing 12. The casing 12 is provided with the side cover plate 15 secured thereto by means of bolts 16, as shown. Suitable packing members 15' are provided between the wall of the casing and sides of the rotor so as to prevent the escape of steam. 60

Referring now particularly to Fig. 2, the numeral 17 designates the inlet connection and 18 the exhaust connection. On the inside face of the casing I provide a plurality of dove-tailed recesses 19, one of which is 70 arranged between the inlet and exhaust connections. Mounted in these dove-tailed recesses are the holding and guiding members 20 which have the dove-tailed portion 21 to fit the dove-tailed recess and also having the 75 laterally extending wind portions 22 which rest against the inside of the casing. Adjustably mounted in each holding and guiding member 20 is the pressure block 23, being located in the recess 24 in the holding 80 and guiding member and adjustable by means of the screw member 25 having the squared head 26. This screw member has the loose connection 27 with the pressure block so as to permit its rotation therein. 85

The rotor is provided on its peripheral face with the plurality of buckets or recesses 28 which are formed as shown, having the abrupt edge 29 and the inclined face 30 leading to a feather edge. These buckets or 90 recesses are arranged close together about the face of the rotor.

The steam is lubricated before entering the engine so that all the bearings are thereby lubricated.

As shown in Fig. 1, I can use both high and low speed engines which may be coupled to work together or separately, according to working conditions. The governor controls or regulates the admission of steam. The 100 rotor will flow in oil, thereby lubricating the packing rings about the sides thereof.

The operation of this mechanism is as follows: The pressure blocks with the exception of the one between the inlet and exhaust 105 connections are withdrawn and steam is admitted through the inlet connection 17, circulating about the casing and rotor and starting the rotation of the rotor. The pressure blocks are adjusted inwardly so as 110

to restrict the circuit of the steam so that more and more of its force is exerted against the buckets 28 and particularly against the abrupt face or wall 29 thereof, thereby 5 gradually increasing the speed of rotation of the rotor. The steam is confined in passing under the pressure blocks and expands on passing each pressure block. The buckets are arranged so that when one is under a 10 pressure block, the supply of steam thereto being cut off, the next one will be subjected to the steam from the inlet connection. This is true in connection with all of the pressure blocks so that a maximum efficiency 15 in operation is obtained.

What I claim is:

1. In combination in a rotary engine, a cylindrical casing, a rotor mounted therein, packing between the sides of the rotor and 20 the casing, said casing having inlet and exhaust connections, a plurality of pressure blocks adjustably mounted in said casing and adapted to be moved toward and from the rotor, one being located between the inlet 25 and exhaust connection, said rotor having a plurality of buckets or sockets provided in the face thereof.

2. In combination in a rotary engine, a cylindrical casing immovably mounted, a 30 rotor mounted therein, packing between the sides of the rotor and casing, said rotor being provided with a plurality of recesses or buckets on its face, said casing having inlet and exhaust connections, a plurality of pressure blocks located at intervals about the 35 casing, one being located between the inlet and exhaust connections.

3. In combination in a rotary engine, a cylindrical casing immovably mounted, a 40 rotor mounted therein, packing between the sides of the rotor and casing, said rotor being provided with a plurality of recesses or buckets on its face, said casing having inlet and exhaust connections, a plurality of pressure blocks located at intervals about the 45 casing, one being located between the inlet and exhaust connections, and means for adjusting the pressure blocks to and from the rotor.

50 4. In combination in a rotary engine, a

cylindrical casing immovably mounted, a rotor mounted therein, packing between the sides of the rotor and casing, said rotor being provided with a plurality of recesses or buckets on its face, said casing having 55 inlet and exhaust connections, said casing having a plurality of guideways, a guiding and holding member mounted in each guideway and a pressure block adjustably supported by each guiding and holding 60 member.

5. In combination in a rotary engine, a cylindrical casing immovably mounted, a rotor mounted therein, packing between the sides of the rotor and casing, said rotor being provided with a plurality of recesses or buckets on its face, said casing having 65 inlet and exhaust connections, said casing having a plurality of dove-tailed guide-ways on the inner face thereof, a guiding and holding member having a dove-tailed portion mounted in each guide-way and said guiding and holding member having a socket in its face, a pressure block slidably mounted in each socket and means extending through 70 the guiding and holding member in casing for moving the pressure block in and out to vary the distance thereof from the face of the rotor.

6. In combination in a rotary engine, a 80 cylindrical casing immovably mounted, a rotor mounted therein, packing between the sides of the rotor and casing, said rotor being provided with a plurality of recesses or buckets on its face, said casing having 85 inlet and exhaust connections, said casing having a plurality of dove-tailed guide-ways on the inner face thereof, a guiding and holding member having a dove-tailed portion mounted in each guide-way and also having 90 wing portions bearing on the inner face of the casing and said guiding and holding member having a socket in its face, a pressure block slidably mounted in each socket and means extending through the guiding 95 and holding member in casing for moving the pressure block in and out to vary the distance thereof from the face of the rotor.

VAN EVERY EDWARDS.
